UNITED STATES PATENT OFFICE.

CHARLES G. MOLIN, OF WARREN, PENNSYLVANIA.

WRENCH.

SPECIFICATION forming part of Letters Patent No. 758,266, dated April 26, 1904.

Application filed June 24, 1903. Serial No. 162,918. (No model.)

To all whom it may concern:

Be it known that I, CHARLES G. MOLIN, a citizen of the United States, residing at Warren, in the county of Warren and State of Pennsylvania, have invented new and useful Improvements in Wrenches, of which the following is a specification.

My invention relates to certain new and useful improvements in that type of tools known as "sliding-jaw" wrenches and wherein one jaw moves relative to the other to clamp and release the inserted nut or piece of work; and my invention consists, essentially, of the combination, with the fixed and movable jaws, said movable jaw having a rack-surface, of an operating-handle carried by a movable eccentric and provided with a toothed head or end adapted by the adjustment of the eccentric to be moved into and out of engagement with the rack-surface of the movable jaw.

My invention also consists in the employment of means connected with the head of the wrench for effecting a quick closing or opening of the jaws independent of the manipulation of the handle or its eccentric.

My invention further consists of the parts and the constructions and combinations of parts, which I will hereinafter describe and claim.

In the accompanying drawings, forming part of this specification, and in which similar letters of reference indicate like parts throughout the several views, Figure 1 represents a side elevation of a wrench embodying my invention. Fig. 2 is an edge view of the same. Fig. 3 is a sectional view of the head, showing the fixed and movable jaws and the toothed head of the handle in engagement with the rack-bar of the movable jaw. Fig. 4 is a view similar to Fig. 3 and showing the toothed head of the handle moved away from and out of connection with the rack-bar of the movable jaw. Figs. 5, 6, and 7 are detached views of the eccentric crank-pin and locking-bolt.

In carrying out my invention I form a head A, which is made rigid with and a part of the stationary jaw b. This head may be made by different methods and of any well-known form, and it is herein shown as having an

opening b^x extending through it in a plane at right angles to the projection of the stationary jaw. The head is also slotted from below to admit the upper or head end of the operating-handle.

The movable jaw c² seats upon the top edge of the head A and opposes the fixed jaw and is provided with a rack-bar c, which extends at right angles to the jaw and is slidably guided in the opening b^x of the head, it being appropriately guided by the side walls of said opening and by suitable screws d or pins passing through the side of the head A and engaging a slot or channel e³ in the side of the rack-bar.

In connection with the sliding jaw and as a means for operating the same I employ a handle a, the upper end of which enters the lower slotted portion of the head A and is provided with a head in the form of a toothed segment, as it is provided with teeth a', which are designed to operatively engage with the teeth of the rack-bar of the movable jaw. The toothed head or upper end of the handle is mounted upon an eccentric-pin e, on the opposite ends of which are fixed the eccentrics in the form of disks e' e'', appropriately rotatively mounted in circular openings in the sides of the head of the fixed jaw, as shown in Fig. 1. In the practical construction of the eccentric-pin I prefer to make one disk removable to enable the pin proper to be placed into the opening in the head of the handle. The pin and the eccentric-disks being to all intents and purposes a single rigid structure, I shall hereinafter refer to them simply as an "eccentric-pin." To the eccentric-pin—say to one of the disk ends thereof—I hingedly attach a locking bolt or clamp f, which furnishes a handle or finger-piece by which the eccentric-pin may be turned in its bearings to raise and lower the toothed end of the handle relative to the rack-bar of the movable jaw, said locking-bolt adapted also to be turned down alongside the head of the fixed jaw and to be forced into engagement with an appropriate opening therein, whereby the eccentric-pin is held against movement. On the handle below the head A is a slide-bar g, slotted upon a guide-pin g' and having its upper

end pivotally connected with a link *h*, which in turn is pivotally connected with a second link *i*, whose upper end is forked and pivotally connected with the head *A*, said links *h* and *i* forming, essentially, a toggle-lever connection between the slide-bar and the head *A*.

From this description it will be apparent that the parts being in the normal position (shown in Fig. 4) when the eccentric-pin is turned—say by means of the locking-bolt *f*—the handle is drawn farther into the head *A* and until the teeth *a* are brought operatively into engagement with the teeth of the rack-bar of the movable jaw, as in Fig. 3. If the handle is now moved to the left, the sliding jaw is caused to approach the fixed jaw, and the nut or piece of work which has been received between the jaws is firmly gripped, and when the eccentric-pin is again turned into the lower position, as shown in Fig. 4, the handle is moved to cause the toothed end thereof to recede relative to the rack-bar of the movable jaw, and thus disengage itself therefrom. When the wrench is in the straight position, (shown in full lines in Fig. 1,) the jaws stand apart or are open to receive the nut or work, and when the latter is appropriately entered and the rack-bar is engaged, as aforesaid, and the handle is moved, say, to the left, the space between the jaws is reduced and inserted article firmly gripped.

The wrench is adapted to fit either a larger or smaller range of work by disengaging the toothed end of the handle from the rack-bar and then moving the jaw *c* to the right or left a distance equal to one or more of the teeth of its rack-bar and then turning the eccentric-pin into its higher position to effect the engagement of the handle with the rack-bar and operating the handle, as before explained. This last-named adjustment increases or decreases the normal size of the opening between the jaws when the parts are in the normal straight position of Fig. 1.

If it is desired to quickly close the jaws upon the nut or other piece of work, the slide-bar *g* is pulled down and the toggle-lever connection *h i* draws the head *A* over, turning upon the disk ends of the eccentric-pin, into the dotted position of Fig. 1, the handle and rack-bar being in engagement when the sliding jaw is rapidly moved relative to the fixed jaw, and when it is desired to quickly open the jaws the aforesaid operation of the slide-bar and its adjuncts in an opposite direction effects the desired movement.

Having thus described my invention, what I claim as new, and desire to secure by Letters Patent, is—

1. In a wrench, the combination of a head having a stationary jaw extension, said head slotted on its under side and provided with a transverse opening; a movable jaw slidably

mounted on said head and having a rack-bar guided in said transverse opening; an eccentric-pin having disk ends rotatively mounted in said head; a locking-bolt hinged to one of the disk ends and adapted to fit in an opening in the head to lock the pin, and to swing outward and serve as a handle for turning said pin; and a handle having a toothed upper end mounted on the pin between said disk ends and adapted, by the rotation of said pin to engage and disengage said rack-bar.

2. In a wrench, the combination of a head having a fixed jaw extension, said head open on its under side and provided with a transverse opening; a movable jaw slidably mounted on the head and having a rack-bar guided in the transverse opening thereof; said rack-bar having a groove or channel in its side and said head having a pin to engage said groove or channel; a handle having a toothed upper end entering the lower end of the head; an eccentric-pin passing through the toothed end of the handle having disk ends rotatively mounted in said head; and a locking-bolt hinged to one of the disk ends and adapted to engage an opening in the head to lock the pin, said bolt being adapted to be turned outwardly from the head to serve as a handle for rotating the pin to cause the toothed end of the handle to be moved into and out of engagement with the rack-bar.

3. In a wrench, the combination of a head provided with a rigid jaw extension; a jaw slideable on the head relative to the rigid jaw, and provided with a rack-bar; a handle provided with a segmental toothed end; an eccentrically-mounted, rotatable pin upon which the handle is carried and by means of which the toothed portion thereof is moved into and out of engagement with the rack-bar; and a member hinged to the pin and adapted to swing outwardly from the head to form a handle for rotating the pin, said member adapted to be forced into locked engagement with the head to maintain the position of the pin and said head having an opening to receive said member.

4. In a wrench, the combination of the head; the fixed and movable jaws; said movable jaw having a rack-bar extension; the handle having a toothed head; the eccentrically-mounted rotatable pin and means including a slide-bar on the handle and a toggle-lever connection between the same and the head for moving said head about said pin and quickly opening and closing the jaws.

In testimony whereof I have hereunto set my hand in presence of two subscribing witnesses.

CHARLES G. MOLIN.
